Primary Examiner — Kevin K. Rudzinski*Assistant Examiner* — Clare Ann Gannon(74) *Attorney, Agent, or Firm* — Gregory Finch; Finch Paolino, LLC(57) **CLAIM**

The ornamental design for a multipurpose towel, as shown and described.

DESCRIPTION

FIG. 1 is an isometric rear view of the multipurpose towel showing the new design in the first configuration with the strap element in a vertical closed position;

FIG. 2 is an isometric rear view thereof, shown in a second configuration with the strap element in a vertical open position;

FIG. 3 is an isometric rear view thereof, shown in a third configuration with the strap element in a horizontal open configuration;

FIG. 4 is a front view thereof, shown in a fourth configuration with the strap element in a horizontal closed configuration;

FIG. 5 is a rear view thereof;

FIG. 6 is a right side view thereof;

FIG. 7 is a left side view thereof;

FIG. 8 is a bottom plan view thereof; and,

FIG. 9 is a top plan view thereof.

The portions of the article shown in broken lines in FIG. 4 are for the purpose of illustrating environmental structure and form no part of the claimed design.

1 Claim, 8 Drawing Sheets(56)
